Primary Examiner — Barbara Fox*Assistant Examiner* — Aram Kwon(74) *Attorney, Agent, or Firm* — Conley Rose, P.C.; J. Robert Brown, Jr.(57) **CLAIM**

The ornamental design for a communication device housing, as shown and described.

DESCRIPTION

FIG. 1 is a front perspective view of a communication device housing in accordance with the new design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is a perspective view of the communication device housing shown in an environment of use.

The broken lines in FIGS. 1–8 depict portions of the communication device housing that form no part of the claimed design. The broken lines around the communication device housing in FIG. 8 depict environment structure that form no part of the claimed design.

1 Claim, 6 Drawing Sheets(56)
